UNITED STATES PATENT OFFICE.

WILLIAM COOPER, OF CHICAGO, ILLINOIS.

MEANS FOR OPERATING REVOLVING CHUCKS.

SPECIFICATION forming part of Letters Patent No. 391,585, dated October 23, 1888.

Application filed February 23, 1888. Serial No. 265,060. (No model.)

To all whom it may concern:

Be it known that I, WILLIAM COOPER, a resident of the city of Chicago, county of Cook, State of Illinois, have invented a certain new 5 and useful Hydrostatic Chuck, of which the following is a specification, reference being had to the accompanying drawings.

My invention relates to revolving chucks of the class in general use for making screws and 10 other small articles; and it consists in operating the chuck by liquid-pressure.

Hitherto complicated constructions of various kinds have been used for clamping the chuck by mechanical pressure to the article to 15 be held. All of such devices are more or less objectionable on account of the slowness of their action, complexity of structure, imperfect control, and the unyielding character of the pressure. Of these defects the unyielding character of the pressure is a very material limitation to the capacity and efficiency of the chuck. The use of liquid overcomes this objection, giving a pressure which is comparatively elastic, automatically adapting itself to the work. The 25 chuck is also simpler in construction, susceptible of easier control, and has a wider range of work.

In the drawings I show a special construction invented by me for the application of the 30 liquid-pressure; but I do not wish to be confined to this construction. I have conceived various other forms well adapted to the purpose. I show this construction simply by way of illustration, as one suitable means of carrying out the process.

Like letters referring to like parts, Figure 1 is a longitudinal vertical section of a revolving chuck operated by liquid-pressure, and Fig. 2 is a front-end view of the same.

40 A A' are a pair of pillow-blocks arranged at a suitable distance apart and constituting a supporting-frame for the chuck.

B B' are boxes rigidly secured to the blocks A A', respectively.

45 C is the chuck-spindle, having its bearings in said boxes and freely revolving therein.

C' is a driving-pulley rigidly secured to the spindle C and coupled to any suitable source of power. (Not shown.)

50 The spindle C is provided with the customary taper hole e, and is otherwise of the usual construction, except that its central part is en-

larged and made hollow, forming a cylinder, C', adapted to receive the liquid for operating the chuck-plunger. The boxes B B' are provided with peripheral flanges b b', respectively, on their inner ends. The ends of the cylinder C' bear against the inner ends of the boxes B B' and the faces of their flanges b b', and the spindle is thereby securely held against longitudinal movement. The cylinder C is provided with the ports c' c" for the inlet and outlet of the liquid.

D is an inclosing-shell closely fitting the cylinder C', and provided on its inner surface with 65 the circumferential grooves d d' in communication with the ports c' and c", respectively. This shell D is also held from longitudinal displacement by the flanges b b' on the boxes B B'.

E is a valve-seat and liquid-chest formed integral with the shell D, and provided with the ports e' e", communicating with the grooves d' and d", respectively, the inlet-pipe F and the outlet-pipes H H'.

The inlet-pipe F communicates with the reservoir G containing liquid under pressure. This may be an ordinary water-main, in case water is used, and the water in the same is kept at a sufficiently high pressure; or it may be any reservoir of any suitable liquid to which the requisite pressure may be given in any suitable way.

K is a double-balanced slide-valve located within the chest E and provided with a stem, 85 k, passing out through a stuffing-box, L, in the end of the chest E. A suitable lever, M, may be pivoted to some suitable support and applied to the stem k for the convenient operation of the valve.

N is the tapering chuck-head, consisting of the ordinary spring jaws or collets rigidly attached to the hollow operating stem or plunger-shaft N', which snugly fits the interior of the spindle C. A part of this shaft N' within 95 the cylinder D is enlarged, forming a piston, N", of the same diameter as the cylinder D. This piston is shorter in length than the cylinder D, the difference being sufficient to give the requisite throw for clamping and releasing 100 the chuck-head N.

P represents a part of the rod of metal from which the articles are made, the same being fed forward through the chuck-shaft in any

suitable way, (not shown,) and clamped in a fixed position by the chuck-head.

The operation is apparent from the description already given. The spindle C and cylinder C' are continuously revolved within the bearings B B' and the shell D by power applied to the pulley C''. Liquid is admitted to one or the other side of the piston N'', moving the chuck-shaft longitudinally, either forcing it into its clamping position or releasing it therefrom at the will of the operator by simply shifting the valve K. In the position shown the cylinder and chest ports e' and e'' and e''' and e''''' are open, the former set communicating with the inlet-pipe F and the latter set with the outlet-pipe H', and the outlet-pipe H is closed. If the valve be thrown to its opposite extreme position, H' would be closed and e' and H and e''' and F, respectively, would be in communication. In mid-position the valve will close both cylinder ports.

I may use water, oil, or any other suitable kind of liquid.

What I claim, and desire to secure by Letters Patent of the United States in this application, is as follows:

1. The combination, with a revolving chuck, of a cylinder adapted to receive a liquid under pressure, and a piston within said cylinder having a connection with said chuck for im-

parting an opening and closing movement thereto, substantially as described.

2. The combination, with a revolving chuck having an enlargement on its stem adapted to serve as a piston, of a cylinder inclosing the enlarged or piston portion of said stem adapted to receive a liquid under pressure and provided with ports for the inlet and outlet of the liquid, and valves for opening and closing said ports, substantially as described. 40

3. The combination, with a revolving chuck having a piston on its stem, of a spindle mounted on said stem having a cylinder inclosing said piston and provided with ports for the inlet and outlet of a liquid, fixed bearings for said spindle adapted to allow rotation and prevent longitudinal movement thereof, a shell inclosing said cylinder having ports in communication with the cylinder-ports and provided with a valve-seat, a hood or chest inclosing said valve-seat in communication with a liquid under pressure and provided with exhaust or outlet ports, and a valve in said chest for controlling the inlet and outlet of the liquid to and from the opposite sides of 55 the piston, substantially as described. 45

WILLIAM COOPER.

In presence of—

GEORGE P. HAMPTON,
JAS. F. WILLIAMSON.
